AUTOMATIC WINDOW CLOSER

Chauncey B. Kauffman and Charles H. Kauffman, Hellam, Pa.

Application July 7, 1936, Serial No. 89,398

12 Claims. (Cl. 268—123)

This invention relates to closure operators, and its general object is to provide a device of that character which is primarily designed for automatically closing a window, in the event of 5 rain or excess moisture passing within the window opening, thereby preventing damage by storms and moisture laden atmosphere.

A further object of the invention is to provide an automatic window closing device that cushions 10 the closing action of the window, thereby preventing damage thereto, as well as to the parts of the device.

Another object is to provide an automatic window closing device that can be attached to either 15 side of the window, as well as enclosed within the sash, so as to be completely hidden from view, when the window is in closed position.

A still further object is to provide an automatic window closing device that can be set, to remain 20 in open position, is easy to install, compact in form, simple in construction, inexpensive to manufacture, and extremely efficient in operation, use and service.

This invention also consists in certain other 25 features of construction and in the combination and arrangement of the several parts, to be hereinafter fully described, illustrated in the accompanying drawings and specifically pointed out in the appended claims.

In describing the invention in detail, reference 30 will be had to the accompanying drawings wherein like characters denote like or corresponding parts throughout the several views, and in which:

Figure 1 is a perspective fragmentary view illustrating one form of the present invention applied to a window.

Figure 2 is a vertical sectional view taken therethrough.

Figure 3 is a fragmentary view illustrating the 40 position of the parts when the window is being closed.

Figure 4 is a sectional view taken approximately on line 4—4 of Figure 2, looking in the direction of the arrows.

Figure 5 is a detail perspective view of the fragile keeper member used with the present device.

Figure 6 is a fragmentary sectional view illustrating a modified form of the present invention applied to a window.

Figure 7 is a fragmentary view of the device per se and taken at right angles to Figure 6.

Figure 8 is a sectional view taken approximately on line 8—8 of Figure 6, looking in the 55 direction of the arrows.

Figure 9 is a sectional view taken approximately on line 9—9 of Figure 8, looking in the direction of the arrows.

Figure 10 is a sectional view taken through the cam bearing cap. 5

Referring to the drawings in detail, and particularly to the form as shown in Figures 1 to 4 inclusive, the letter A indicates the base of a window frame and B the lower sash which together with the base has our device attached 10 thereto, as clearly shown in Figure 1.

The device includes a cylinder 1 having a closed upper end 2 which has formed therewith a right angle extension 3, provided with openings to receive securing means such as screws, as shown, 15 for fixing the cylinder to the sash B, for disposition in depending relation with respect thereto.

The lower end of the cylinder is closed by a cap 4 which is threaded thereon and provided with an opening for the passage of a piston rod 5 therethrough, the latter having secured to its upper end a piston 6 of the cup washer type, as shown. Surrounding the rod 5 and having its end convolutions engaging the piston 6 and the cap 4, is a coil spring 7, for the purpose of urging the cylinder downwardly on its piston. It will be obvious that as the cylinder is being moved downwardly, the piston will naturally compress air therein, and therefore set up a cushioning action. The air is released by a bleed port controlled by a screw valve 8 provided with a groove 9 longitudinally arranged therein and which decreases in depth from the inner to the outer end thereof, so that the amount of air passing through the groove can be regulated, as will be apparent 30 upon inspection of Figure 2.

The rod 5 has arranged at intervals in its length the notches 10 of the cam type, in that they are provided with inclined walls that merge into rounded seats in the lower ends thereof for the purpose of receiving the pin 11 of a dog 12 40 which is pivotally mounted on the cap 4 and spring pressed for normally retaining the pin thereof within one of the notches to hold the window in open position, as clearly shown in Figure 1. However, the rod 5 is rotatable to move the notches 10 out of the path of the dog 12, to allow the window to close by the action of the spring, in this form of the invention.

The lower end of the rod 5 is mounted for 50 rotation within a sleeve 13 that is formed on and rises from a base plate 14, the latter having apertures therein to receive screws or the like, to be fixed to the base A of the window frame, as clearly shown in Figure 1, and the 55

sleeve 13 has its open free end closed by a cap 15 which is fixed to the rod by a set screw or the like.

Extending from the sleeve is a bracket 16 which has fixed thereto an arm 17, the latter extending horizontally therefrom for cooperation with an arm 18, that is threaded or otherwise secured to the rod 5, for horizontal swinging movement within a slot 19 that extends for a portion of its circumference of the sleeve 13, whereby the arm 18 can be disposed parallel with the arm 17 or at right angles thereto, as shown in full and dotted lines in Figure 4.

The rod is urged to a position for disposing the notches 10 out of the path of the dog 12, by a coil spring 20 that surrounds that portion of the rod within the sleeve and has one end fixed to the sleeve and its opposite end to the rod, as clearly shown in Figures 2 and 4, it being obvious that when the notches are disposed out of the path of the dog, the arm 18 is arranged at right angles with respect to the arm 17, and of course these arms are parallel when the notches are disposed in the path of the dog, as best shown in Figure 1.

In order to hold the parts in the position of Figure 1, with the window open as shown, we employ a fragile keeper strip 21 which of course acts in the capacity as a moisture responsive means and as best shown in Figure 5, is preferably an elongated strip of paper having its end portions secured together by suitable adhesive means 22, to provide a band for disposal about the free end portions of the arms 17 and 18.

We likewise employ manually actuated means for holding the parts against movement, and in the form as shown, the arm 18 has slidably mounted thereon a collar 23 which is limited in its movement by a pin 24, and the inner end 40 of the collar 23 is provided with lugs 25 that are receivable in recesses 26 arranged at one end of the slot 19, and in the upper and lower walls thereof, as best shown in Figure 1, consequently when the lugs 25 are mounted in the recesses 45 26, it will be obvious that the device is held against movement, but when the device is set to be acted upon by moisture or rain water the collar 23 is moved to the full line position of Figure 4, and in the event the strip or band 21 becomes broken the spring 20 will rotate the rod 5 for disposing the notches 10 out of the path of the dog 12, and thereby result in the window being closed by the action of the coil spring 7.

In Figures 6 to 10 inclusive, we have illustrated a modified form of our window closing device, which likewise includes a cylinder 27 which is mounted within the lower sash of the window, the sash being provided with a bore for that purpose, and the cylinder likewise has a closed upper end having a screw valve 28 extending therethrough to release air from the cylinder. The lower end of the cylinder is closed by a cap 29 which has extending therethrough the rod 30 of the piston 31 and the rod is also provided with notches 32 to receive the bight portion of a substantially ball type dog 33 the latter being spring pressed by a leaf spring 34 that holds the dog within one of the notches, as shown.

The lower end of the rod 30 is mounted for rotation within a sleeve 35 that likewise includes a base plate 36 adapted to be secured to the base of a window frame by screws or the like, as shown, and the upper end of the sleeve 35 is closed by a cap 37 that is mounted for ver-

tical movement on the rod, but is limited in its upward direction by a collar 38 that is fixed to the rod 30. The sleeve 35 is provided with lugs 39 rising therefrom and diametrically opposed with respect to each other to be received in like disposed recesses arranged in the cap 37 which also has a cam lug 40 formed on and depending from the inner surface thereof, as best shown in Figure 10.

Extending through the rod 30 is a pin 41, and the rod is held against movement by the cam lug 40 being disposed in the path of one of the projecting portions of the pin 41, it being obvious that the cap must be raised for disposing the lug 40 out of said path, to allow the rod 15 to be rotated, and the rod is rotated by a coil spring 42 in the same manner, as described in the form shown in Figures 1 to 4 inclusive.

Formed on the base plate 36 and including the horizontal portion is an arm 43, and cooperating with the arm 43 is an arm 44 that is formed on the cap 37 and which likewise includes a horizontal portion to receive, with the horizontal portion of the arm 43, the moisture responsive means which is also shown in this form of the invention, as being a strip 45, held in band formation by adhesive means, as suggested in Figure 6.

In order to rotate the rod 30 to set position, we employ a handle 46, that is preferably identical with the arm 18, and which is movable in a slot 47 extending for a part of the circumference of the sleeve 35, which also has recesses therein to receive the lugs of a collar 48 similar to the collar 23, to hold the parts against movement regardless of whether or not the strip or band 45 is used.

When the device of the form just described is disposed in set position to be acted upon by moisture or the like, the parts are arranged as shown in Figure 9. Assuming that the strip or band 45 breaks, it will be obvious that the cap 37 is raised to move the cam lug 40 out of the path of the pin 41, thereby allowing the coil spring 42 to rotate the rod 30 and consequently the notch away from the dog 33, which of course will result in the window being lowered to closed position, it being understood that a coil spring may be used for that purpose and in that instance the spring will be disposed about the rod 30, between the cap 29 and the piston 31. However, the coil spring is not necessary in the event the sash is not counterbalanced by the usual weights, as the sash will then drop by gravity, as will be apparent.

The sash is provided with a recess 49 in the lower end thereof to cooperate with the bore in receiving the parts mounted on the base of the frame, so that it will be obvious that the entire device is hidden from view when the window is closed.

It is thought from the foregoing description that the advantages and novel features of the invention will be readily apparent.

It is to be understood that changes may be made in the construction and in the combination and arrangement of the several parts, provided that such changes fall within the scope of the appended claims.

What we claim is:

1. A closing device for a window, comprising means for retaining the window in open position and including a rotatably mounted rod, ratchet means for said rod to hold the retaining means active, means for rotating said rod to release

- the latter from the ratchet means, and means for holding the rotating means against movement and including means responsive to moisture for releasing the same.
5. A closing device for a window, comprising means for retaining the window in open position and including a rotatably mounted rod, ratchet means for the rod to hold the retaining means active, means surrounding the rod for rotating the latter and to release it from the ratchet means, means including a movable arm having connection with said rod for holding the rotating means against movement, a stationary arm, and means disposed about the arms to hold the movable arm against movement and being responsive to moisture for releasing the same.
10. A closing device for a window, comprising means for retaining the window in open position and including a cylinder carried by the window, a piston in said cylinder, a rotatably mounted rod for the piston, ratchet means for the rod to hold the retaining means active, means surrounding the rod for rotating the latter and to release it from the ratchet means, means including a movable arm having connection with said rod for holding the rotating means against movement, a stationary arm, and a fragile band disposed about the arms to hold the movable arm against movement and being responsive to moisture for releasing the same.
15. A closing device for a window comprising a cylinder carried by the window, a piston in the cylinder, a rod for the piston and mounted for rotation, said rod having notches therein along the length thereof, a dog carried by the cylinder and engageable in any one of the notches for holding the window in open position, means surrounding the rod for rotating the latter to move the dog out of the notch, means including a movable arm having connection with said rod for holding the rotating means against movement, a stationary arm, means disposed about the arms to hold the movable arm against movement and being responsive to moisture for releasing the same, and means to release air from the cylinder to retard movement of the piston during the closing action of the window.
20. A closing device for a window, comprising a cylinder carried by the sash of the window, a piston in the cylinder, a rod for the piston and mounted for rotation, ratchet means for said rod to hold the sash in open position, a sleeve fixed to the window frame and having the lower end of the rod mounted therein, a spring in the sleeve and secured thereto and the rod respectively for rotating the latter to release the same from the ratchet means, means for holding the rod against rotation and including means responsive to moisture for releasing the same.
25. A closing device for a window comprising a cylinder carried by the sash of the window, a piston in the cylinder, a rod for the piston and extending through the cylinder, said rod being mounted for rotation, a sleeve secured to the frame of the window and receiving the lower end of the rod, ratchet means for the rod to hold the sash in open position, an arm secured to the rod, a stationary arm secured to the sleeve, means surrounding the arms to hold the rod carried arm against movement and being breakable under the action of moisture to release the latter, and adjustable means for releasing air from the cylinder.
30. A closing device for a window, comprising a cylinder carried by a sash of the window, a piston mounted in the cylinder, a rod for the piston and extending through the lower end of the cylinder, said rod being mounted for rotation and having notches arranged along the length thereof, a dog carried by the cylinder and receivable in any one of the notches to hold the sash in open position, a sleeve having the lower end of the rod mounted therein, spring means in said sleeve for rotating the rod and to release the dog from its notch, an arm secured to the rod for movement therewith, a stationary arm secured to the sleeve, means surrounding the arms to hold the rod carried arm against movement and being responsive to moisture to release the same, and latching means to hold the rod carried arm against movement.
35. A closing device for a window, comprising means for retaining the window in open position and including a rotatably mounted rod, ratchet means for said rod to hold the retaining means inactive, a sleeve fixed to the window frame and receiving the lower end of said rod, spring means in said sleeve and secured thereto and the rod respectively for rotating the latter, said sleeve having a circumferentially disposed slot therein, an arm secured to the rod and extending through the slot, an arm fixed to the sleeve, fragile means breakable under the action of moisture and surrounding the arms to hold the rod carried arm against movement, and latching means for the rod carried arm to prevent operation of the closing device.
40. A closing device for a window, comprising means for retaining the window in open position and including a rotatably mounted rod, ratchet means for said rod to hold the retaining means inactive, a sleeve secured to the window frame and receiving the lower end of said rod, spring means in said sleeve for rotating the rod to release the latter from the ratchet means, cam means carried by the rod and sleeve respectively to hold the rod against rotation, and means including moisture responsive means for releasing the cam means.
45. A closing device for a window, comprising means for retaining the window in open position and including a rotatably mounted rod, ratchet means for said rod to hold the retaining means inactive, a sleeve secured to the window frame and receiving the lower end of said rod, spring means in said sleeve for rotating the rod to release the latter from the ratchet means, cam means carried by the rod and sleeve respectively to hold the rod against rotation, means including moisture responsive means for releasing the cam means, means for moving the rod against the action of the spring to set the means including the moisture responsive means in operative position, and latching means for the moving means.
50. A closing device for a window, comprising a cylinder carried by and embedded within a sash of the window, a piston in the cylinder, a rod for the piston and extending through the lower end of the cylinder, said rod mounted for rotation and having notches along the length thereof, a spring pressed dog receivable in any one of the notches to hold the sash in open position, spring means for rotating the rod to release the dog from its notch, cam means for holding the spring means under tension, and means for releasing the cam means and including moisture responsive means.
55. A closing device for a window, comprising a cylinder embedded in and carried by a sash of the window, a piston in the cylinder, a rod for the piston and extending through the lower end of the cylinder, said rod mounted for rotation and having notches along the length thereof, a spring pressed dog receivable in any one of the notches to hold the sash in open position, spring means for rotating the rod to release the dog from its notch, cam means for holding the spring means under tension, and means for releasing the cam means and including moisture responsive means.
60. A closing device for a window, comprising a cylinder carried by and embedded within a sash of the window, a piston in the cylinder, a rod for the piston and extending through the lower end of the cylinder, said rod mounted for rotation and having notches along the length thereof, a spring pressed dog receivable in any one of the notches to hold the sash in open position, spring means for rotating the rod to release the dog from its notch, cam means for holding the spring means under tension, and means for releasing the cam means and including moisture responsive means.
65. A closing device for a window, comprising a cylinder carried by and embedded within a sash of the window, a piston in the cylinder, a rod for the piston and extending through the lower end of the cylinder, said rod mounted for rotation and having notches along the length thereof, a spring pressed dog receivable in any one of the notches to hold the sash in open position, spring means for rotating the rod to release the dog from its notch, cam means for holding the spring means under tension, and means for releasing the cam means and including moisture responsive means.
70. A closing device for a window, comprising a cylinder embedded in and carried by a sash of the window, a piston in the cylinder, a rod for the piston and extending through the lower end of the cylinder, said rod mounted for rotation and having notches along the length thereof, a spring pressed dog receivable in any one of the notches to hold the sash in open position, spring means for rotating the rod to release the dog from its notch, cam means for holding the spring means under tension, and means for releasing the cam means and including moisture responsive means.
75. A closing device for a window, comprising a cylinder carried by a sash of the window, a piston

the cylinder, said rod being mounted for rotation, ratchet means for said rod to hold the sash in open position, a sleeve secured to the window frame and receiving the lower end of said rod, spring means in the sleeve for rotating the rod to release the latter from the ratchet means, a cap for the sleeve and movable vertically on the rod, a pin extending through the rod, cam means de-

pending from the cap in the path of the pin to prevent rotation of the rod, and means for holding the cap against movement and including means breakable under the action of moisture to release the cap.

CHAUNCEY B. KAUFFMAN.
CHARLES H. KAUFFMAN.
